UNITED STATES PATENT OFFICE.

EMIL ANDERSON, OF NEW YORK, N. Y., ASSIGNOR TO THE UNIVERSAL TURBINE COMPANY, OF NEWARK, NEW JERSEY, A CORPORATION OF NEW JERSEY.

TURBINE.

1,138,173.

Specification of Letters Patent.

Patented May 4, 1915.

Application filed October 4, 1913. Serial No. 793,421.

To all whom it may concern:

Be it known that I, EMIL ANDERSON, a citizen of the United States of America, and a resident of New York, county and State 5 of New York, have invented certain new and useful Improvements in Turbine-Engines, of which the following is a specification, reference being had to the accompanying drawings, forming a part thereof.

10 My invention relates to improvements in turbines, and its object is to provide a simple and efficient apparatus of this character.

I will describe my invention in the following specification, and then point out the 15 novel features thereof in appended claims.

Referring to the drawings: Figure 1 is a sectional side elevation of a simple form of turbine embodying the present invention. Fig. 2 is an end elevation of the apparatus 20 which is shown in Fig. 1 with certain parts broken away, and some of the parts shown in section in order to illustrate clearly the construction. A portion of the rotor is shown in transverse sections in Figs. 3 and 25 4 on a somewhat enlarged scale. These views are taken at right angles to each other, the section in Fig. 3 being taken on the line 3-3 of Fig. 4 and the section in Fig. 4 being taken on the line 4-4 of Fig. 3. One of 30 the partition plates which is used in the construction of the rotor of the preceding figures is shown in edge view and in plan view respectively in Figs. 5 and 6. Fig. 7 is a plan view of one of the rotor blades, 35 and Fig. 8 a sectional edge view of the same. Another of the rotor blades is shown in plan view in Fig. 9. Certain parts of another form of turbine embodying this same invention, is shown in sectional end view in Fig. 40 10. A turbine which is made according to my invention and which embodies a development of the same idea, is illustrated in sectional side elevation in Fig. 11. The same turbine is shown in end elevation in Fig. 12 45 with some of its parts broken away and with some of its parts shown in section. Details of the construction of the turbine of Figs. 11 and 12 are shown in the succeeding figures of which Fig. 13 is a top plan view 50 of one of the nozzle blocks with a portion of the rotor under it, and Fig. 14 a similar

view with the nozzle block removed. Fig. 15 is a sectional end elevation of one of the nozzle blocks and of an adjacent part of the rotor. An inverted plan view of the nozzle 55 block is shown in Fig. 16. One of the partition plates of the rotor is shown in detail in plan and edge views in Fig. 17. One of the rotor blades is shown in plan and side elevation in Fig. 18. Another of the rotor 60 blades is shown in side elevation and in plan view in Fig. 19, and a rotor blade of another form is shown in plan view in Fig. 20.

Like characters of reference designate corresponding parts in all the figures. 65

The turbine shown in Figs. 1 and 2 comprises an annular casing 10 formed of two parts 11 and 12 bolted together as at 13. To these parts are secured the bearings 14-14 of the rotor shaft 20. Secured to the rotor shaft is a disk 21 upon which is carried the rotor ring. This rotor ring is built up between two flat annular side plates 22 and 23 and a rim flange 24. Between these parts are secured at equal intervals the transverse 70 partition plates 25, by means of lugs 26 which fit into holes in the side plates 22 and 23 and a lug 27 which fits into a hole in the rim flange 24. In each of the compartments formed between the side plates by these 75 transverse partition plates and secured to the plate side 23 is a wavy or corrugated rotor blade 30, the outer end of which is bent over as at 31. 28 is a pin secured to the plate 23 to strengthen and support the part 80 31 of this rotor blade. Opposite this blade is a shorter wavy rotor blade 32 which is parallel with the wavy part of blade 30 and which is secured to plate 22. An intermediate wavy rotor blade 33 is between the blades 85 30 and 32 and parallel therewith. This one is of the same size and shape as the blade 32 but is provided on one of its edges with lugs 34 which fit into holes 29 in the adjacent partition plate 25 and on its opposite 90 edge with lugs 35 which fit into similar holes in the other adjacent partition plate. The casing part 11 is constructed to form an annular chamber 15 with which a pipe 16, from a suitable source of motive fluid supply, is connected. Inside of this casing member and secured thereto at intervals are 95 100

the nozzle blocks 17, each of which is divided by plates 18 into a plurality of outward flow expansion nozzles, and each of which is provided with a valve-controlled port 19 communicating with the chamber 15.

Before specifically describing the other figures of the drawings, I will explain the operation of the form of turbine which is illustrated in the first nine figures of the drawings. Motive fluid, such for example as steam, is admitted through the ports 19 into the nozzle blocks and is delivered under practically no pressure but at high velocity from the expansion nozzles into the rotor ring. Here its direction is changed from side to side as it passes through the zigzag channels formed between the wavy rotor blades. At each deflection of its path some of its velocity is given up and is changed into kinetic energy as it causes the rotor and its shaft to be driven. After the motive fluid leaves the ends of the zigzag paths at the outer edges of the rotor blades 32 and 33 it is deflected over and backward by the curved part 31 of the rotor blades 30. These parts are so positioned that their effect upon the motive fluid causes a reaction which is a further driving impulse. The fluid is then discharged at low velocity into an enlarged portion 36 of the casing from which it passes through an exhaust pipe 37 to condensers or to the air. This turbine although of extremely simple and substantial construction is capable of developing high power with but little consumption of motive fluid. In other words, it is an apparatus of high efficiency.

In Fig. 10 the nozzles 38 are on the outside of the ring arranged to direct the motive fluid inwardly and the rotor blades are reversed in position. The operation of this form of turbine is otherwise substantially the same as that which has been described. A further development of the same idea is embodied in the turbine which is illustrated in the remaining figures of the drawings. This, as may be seen from Figs. 11 and 12, comprises a casing of two annular parts which in this case are designated by 41 and 42 which support the bearings 44 for the rotor shaft 50. The casing part 41 is constructed to form an annular chamber 45 with which the motive fluid supply is connected at 46. Affixed to this part of the casing at equally spaced intervals, are the nozzle blocks 47 which are in communication with the chamber 45 through ports 49, all but one of which is valve-controlled. Referring to Figs. 13, 15 and 16, it will be seen that these nozzle blocks are each constructed to form two passages, the first of which, designated by 40, is a narrow expansion nozzle adapted to direct the motive fluid inwardly into the rotor ring. The other passage is curved and comprises an

intake port 43 and an expansion nozzle 48 of greater width than that of nozzle 40 but with one of its sides in alignment with one side of the nozzle 40. The rotor comprises two side plates 51 and 52 which are mounted upon shaft 50 and which support the other parts of the rotor. The partition plates 53 are constructed with ears 54 projecting from their opposite edges. These ears fit into narrow recesses in the side plates 51-52 and after they are in place with the rotor blades which I will describe presently, are supported in the side plates by means of bolts or rivets 55 which pass through the side plates and draw them together against the edges of the division plates. As in the other structure, there are between adjacent partition plates three rotor blades. One of these, designated by 60, has end flanges 61 which fit into transverse slits in the rims of the side plates, a wavy portion 62, and another part 63 bent on a longer curve. It also has lugs 64 projecting from its opposite edges which fit into holes 56 in the partition plates. Another, 65, of the rotor blades has a straight portion 66 and a wavy portion 67 and from its edges project lugs 68 which fit into holes 57 in the partition plates. The third rotor blade 70 has a straight portion 71, a wavy portion 72, and its end is bent back as at 73. From its edges project lugs 74 which fit into holes 58 in the partition plates. When these parts are assembled, as in Fig. 14, the straight parts 66 and 74 of rotor blades 65 and 70 are parallel with side plate 52, the wavy portions of all three rotor blades in each compartment between adjacent partition plates are parallel with one another and the part 63 of each rotor blade closes its respective compartment.

In the operation of this apparatus the motive fluid is directed by nozzle 40 into the compartments between the side plate 51 and the part 66 of rotor blade 65. It then passes through the passage formed between the parallel wavy parts of the rotor blades 60 and 65 where it is deflected from side to side, giving up some of its velocity and driving the rotor. When it reaches the end of the short rotor blades 65 and 70, it is allowed to expand and is at the same time turned back by the part 63 of blade 60, giving a further driving impulse to the rotor. It then enters the nozzle block 47 at the port 43 and in the block is turned again and directed through expansion nozzle 48 into the rotor. This time it enters the two passages between the blades 60 and 65, and 65 and 70, where it is again deflected from side to side after which it is again deflected by the part 63 of blade 60, this time escaping into the chamber 75 within the casing, from which it is discharged through the exhaust 76.

The operation described may be performed in either case with the nozzles in 120

one of the nozzle blocks. Obviously more power will be developed when the valves to more than one nozzle block are opened, and more or less of these nozzle blocks may be 5 made active according to the amount of power desired.

It is to be noted that both of the turbines which have been described, while differing in construction, operate on the same principle, although in the second form of apparatus the motive fluid is passed twice through the rotor. I have described these different constructions to show that the invention is not limited to any particular form 15 or design of apparatus.

What I claim is:

1. A turbine engine rotor comprising a ring divided obliquely to its radii into a plurality of compartments, a set of rotor 20 blades in each compartment dividing it into a plurality of parallel channels, one of said blades extending beyond the parallel channels and curved over the ends of the other rotor blades.
2. A turbine engine rotor comprising a ring, having therein partition plates dividing said rotor ring into a plurality of compartments, a set of wavy rotor blades in each compartment dividing it into a plurality 30 of parallel tortuous channels, one of the outer of said blades extending beyond the parallel channels and curved over the ends of the other rotor blades.
3. A turbine engine rotor comprising a pair of side plates, partition plates secured thereto at intervals, a set of three rotor 35 blades dividing the spaces between the partition plates into a pair of parallel channels, one of the outer of said rotor blades being longer than the others and extending in a curve over and beyond the ends of the shorter blades.

4. A turbine engine rotor comprising a pair of parallel side plates, partition plates 45 secured thereto at equal intervals, a set of three wavy rotor blades dividing the spaces between the partition plates into a pair of parallel tortuous channels, one of the outer of said rotor blades being longer than the others and extending in a curve over and beyond the ends of the shorter blades.

5. A turbine engine having a rotor comprising a rotor ring divided obliquely to its radii into a plurality of compartments, a set 55 of rotor blades in each compartment dividing it into a plurality of parallel channels, one of said blades extending beyond the parallel channels and curved over the ends of the other rotor blades, and a nozzle arranged to direct motive fluid into said channels.

6. A turbine engine having a rotor comprising a rotor ring, means therein dividing said ring into a plurality of compartments, 60 a set of wavy rotor blades in each compart-

ment dividing it into a plurality of parallel tortuous channels, one of the outer of said blades extending beyond the parallel channels and curved over the ends of the other rotor blades, and a plurality of nozzles arranged to direct motive fluid into said channels. 70

7. A turbine engine having a rotor comprising a pair of parallel side plates, partition plates secured thereto at equal intervals, a set of three wavy rotor blades dividing the spaces between the partition plates into a pair of parallel tortuous channels, one of the outer of said rotor blades being longer than the others and extending in a curve 75 over and beyond the ends of the shorter blades, and a plurality of nozzles arranged to direct motive fluid into said channels.

8. A turbine engine having a rotor comprising a rotor ring divided obliquely to its radii into a plurality of compartments, a set 85 of rotor blades in each compartment dividing it into a plurality of parallel channels, one of said blades extending beyond the parallel channels and curved over the ends of the other rotor blades, a nozzle arranged to direct motive fluid into a part of said channels and a nozzle passage arranged to receive said motive fluid from said part of the channels and to direct it back into more 90 of the channels.

9. A turbine engine having a rotor comprising a rotor ring having means therein dividing it obliquely to its radii into a plurality of compartments, a set of wavy rotor 100 blades in each compartment dividing it into a plurality of parallel tortuous channels, one of the outer of said blades extending beyond the parallel channels and curved over the ends of the other rotor blades, a nozzle arranged to direct motive fluid into a part 105 of said channels, and a nozzle passage arranged to receive said motive fluid from said part of the channels and to direct it back into more of the channels. 110

10. A turbine engine having a rotor comprising a pair of side plates, partition plates secured thereto at intervals, a set of three rotor blades dividing each of the spaces between the partition plates into a pair of 115 parallel channels, one of the outer of said rotor blades being longer than the others and extending in a curve over and beyond the ends of the shorter blades, a nozzle arranged to direct motive fluid into a part of said channels and a nozzle passage arranged to receive said motive fluid from said part of the channels and to direct it back into more of the channels. 120

11. A turbine engine having a rotor comprising a pair of parallel side plates, partition plates secured thereto at equal intervals, a set of three wavy rotor blades dividing the spaces between the partition plates into a pair of parallel tortuous channels, one 130

of the outer of said rotor blades being longer than the others and extending in a curve over and beyond the ends of the shorter blades, and a plurality of nozzle blocks about the outer periphery of the rotor, each of said nozzle blocks being constructed to form an expansion nozzle arranged to direct motive fluid into one of said channels, and a tortuous passage arranged to receive said motive

fluid from said channel and to direct it back 10 into both of the channels.

In witness whereof, I have hereunto set my hand this 3rd day of October 1913.

EMIL ANDERSON.
